[57] **ABSTRACT**

Closure mold between flat surface of building and adjacent edge of building panel having structural member along edge thereof. First flexible strip spans edge of panel with one side of strip along and secured to adjacent portion of structural member. Second flexible strip integral with side of first strip opposite said one side and extends angularly therefrom along-side and inwardly of edge of building panel.

CLOSURE MOLD FOR BUILDING PANELS

BACKGROUND OF THE INVENTION

This invention relates to a closure mold for building panels and more particularly to a closure mold adapted for use between abutting flat surfaces of a building, such as adjacent panels or a ceiling member and an adjacent edge of a building panel, such as a wall having a structural member extending along an edge thereof, whereby the edge is covered.

As is well known in the art to which my invention relates, it is difficult to form prefabricated wall and ceiling panels whereby they fit flush with a flat surface adjacent thereto at all times. It is very desirable to provide a closure mold which is adapted for use with building panels whereby the space between the edge of the building panel and the flat surface adjacent thereto is covered by merely positioning the closure mold at the point of juncture of the building panel and the flat surface. Also, it has been difficult heretofore to secure closure molds to panellike members, such as sheetrock and the like, due to the fact that such building panels are relatively soft and will not retain the securing means for the mold in place.

BRIEF SUMMARY OF THE INVENTION

In accordance with my present invention, I provide a closure mold for use between a flat surface of a building and an adjacent edge of a building panel having a structural member extending along the edge thereof. An elongated flexible strip spans the edge of the panel with one side of the strip extending alongside and secured to an adjacent portion of the structural member. A second elongated flexible strip is formed integrally with the side of the first-mentioned strip opposite the side thereof secured to the structural member and extends angularly therefrom alongside and inwardly of the edge of the building panel to thus cover the point of juncture between the edge of the panel and the adjacent flat surface.

A building structure illustrating the manner in which my improved closure mold is constructed and erected is shown in the accompanying drawing, forming a part of this application, in which:

FIG. 1 is a vertical sectional view through a partition wall having my improved closure mold associated therewith;

FIG. 2 is a fragmental view taken from one side of the structure shown in FIG. 1; and,

FIG. 3 is an enlarged, fragmental sectional view showing the closure mold mounted between the building panel and a flat surface, such as a ceiling or adjacent panel of a partition wall.

Referring now to the drawing for a better understanding of my invention, I show a partition wall comprising the usual wall panels 10 formed of sheet material, such as sheetrock. Secured to and extending between the building panels 10 are elongated structural members 11. Each structural member 11 is preferably in the form of a wood member which extends flush with the adjacent edges of the building panels 10, as shown. The lowermost structural member 11 is secured to the usual subfloor of a building while the uppermost structural member abuts the ceiling 12 for the building.

As shown in FIGS. 1 and 3, the closure mold employed between adjacent walls of a building or between a wall and the ceiling is shown generally at 16 and comprises a first, elongated flexible strip 17 of a width to span the adjacent edge of the building panel 10 with one side of the strip 17 extending alongside an adjacent portion of a structural member 11, as shown. The portion of the flexible strip 17 extending alongside the structural member 11 is secured to the structural member by suitable means, such as a nail 18. Formed integrally with the other side of the flexible strip 17 is a second, elongated flexible member 19 which extends angularly from the flexible strip 17 alongside and inwardly of the adjacent edge of the building panel 10 to thus cover the same.

The elongated flexible strip 17 is provided with a longitudinally extending portion adjacent the elongated flexible strip 19 which extends angularly in an outward direction away from the adjacent edge of the building panel 10. That is, the flexible

strip 17 is bent as at 21 whereby the end of the flexible member 17 opposite the end secured by nail 18 is adapted to flex toward the adjacent edge of the building panel 10 upon moving the panel 10 toward the flat surface 12 which may be in the form of an adjacent wall or ceiling. As shown in FIG. 3, the free end of the flexible strip 19 extends inwardly toward the adjacent side of the building panel 10 whereby it engages the building panel with a snug fit. In FIG. 1, I show the closure mold 16 in the position assumed where the building panel 10 and the adjacent flat surface 12 are both straight and in substantial contact with each other whereby the flexible member is flexed to a generally straight line position. On the other hand, FIG. 3 shows the position of the cover strip 17 where the wall is bowed or there is a substantial gap between the flat surface 12 and the adjacent edge of the building panel 10. Since the flexible member 17 is movable or bendable about the point 21 from the position shown in FIG. 3 to the position shown in FIG. 1, the closure mold 16 shown in FIGS. 1 and 3 adjusts itself automatically to compensate for any gap between the flat surface 12 and the adjacent edge of the building panel 10. While I have shown in FIG. 1 the building panel 10 as abutting a ceiling 12, it will be apparent that the closure mold 16 may be mounted between the vertical edge of a building panel 10 and an adjacent wall structure.

From the foregoing description, the operation and erection of my improved closure mold will be readily understood. The flexible strips 17 are secured rigidly to the structural members 11 adjacent the edges of the building panels 10, as shown. As the adjacent edge of the building panel 10 is moved toward the surface of the ceiling or wall 12 the free end of the flexible strip 17 is adapted to move from the position shown in FIG. 3 to the position shown in FIG. 1 or any intermediate position to thus compensate for any space left between the surface 12 and the adjacent edge of the building panel 10. As the elongated flexible strip 19 moves downwardly alongside the building panel 10, it engages the building panel with a snug fit whereby no space is left between the strip 19 and the adjacent surface of the building panel.

From the foregoing, it will be seen that I have devised an improved closure mold for building panels. By providing a flexible member which is secured firmly to the structural member which is mounted alongside the edges of the panel and providing a second elongated flexible strip which is formed integrally with the first elongated flexible strip and extends angularly therefrom alongside and inwardly of the adjacent edge of the building panel, the adjacent edge is completely covered. Also, by providing the flexible strip 17 with a bent portion 21 which permits the free end thereof to compensate for any space left between the flat surface 12 and the adjacent edge of the panel 10, I eliminate entirely unsightly gaps or spaces between the abutting surfaces.

While I have shown my invention in but one form, it will be obvious to those skilled in the art that it is not so limited, but it is susceptible of various changes and modifications without departing from the spirit thereof.

What I claim is:

1. In a closure mold for use in combination with a flat surface and an adjacent edge of a building panel having a structural member extending along said edge:
  - a. a first elongated flexible strip of a width to span said edge of the panel with one side of said strip adjacent one end of said strip extending alongside an adjacent portion of said structural member,
  - b. means securing said strip to said adjacent portion of said structural member,
  - c. a second elongated flexible strip formed integrally with said first elongated flexible strip at the end thereof opposite said one end and extending angularly therefrom alongside and inwardly of said edge of the building panel so that said edge is covered, and
  - d. a longitudinally extending portion on said first elongated flexible strip adjacent said second elongated flexible strip extending angularly in an outward direction away from

said edge of said building panel so that upon movement of said edge of said building panel toward said flat surface said angularly extending portion of said first elongated flexible strip flexes inwardly toward said one edge.

2. A closure mold as defined in claim 1 in which said second 5 elongated flexible strip extends inwardly toward the side of said building panel.
